(57) **CLAIM**

The ornamental design for an all terrain vehicle, as shown and described.

DESCRIPTION

FIG. 1 is a front view of the all terrain vehicle according to the invention.

FIG. 2 is a rear view of the all terrain vehicle according to the invention.

FIG. 3 is a left side view of the all terrain vehicle according to the invention.

FIG. 4 is a right side view of the all terrain vehicle according to the invention.

FIG. 5 is a top view of the all terrain vehicle according to the invention; and,

FIG. 6 is a perspective side view of the all terrain vehicle according to the invention.

The portions shown in broken lines form no part of the claimed design.
